HAIRPIN

Anthony V. Richetti, Jamestown, N. Y.

Application May 16, 1950, Serial No. 162,370

5 Claims. (CL 132—50)

1

This invention relates to hairpins and more particularly to the type that includes a pair of arms which, through their spring-like action, serve to clamp onto and grasp and hold locks or strands of hair.

Hairpins of the class to which the invention relates are commonly known as "bobby-pins" and all such pins are made from spring-like material in order that the arms may have some measure of clamping action on strands of hair for the purpose of holding such strands in a given position. Many such hairpins have been developed and placed on the market and, to some extent, have served their intended purpose. However, if the many stray hairpins, that can be observed almost anywhere, are any indication, it would appear that currently available hairpins of this type are not entirely satisfactory. This is indicated not only from the fact that these pins actually drop out of the coiffure in which they are placed, but also from the readily observed necessity of a user of such hairpins to ordinarily apply an excessive number of them in order to secure any given coiffure in place. It might be mentioned that the manufacturers of several styles of hairpins now on the market have recognized the inability of the earlier products to serve their intended purpose for any continuing period, and have, as a result, improved or increased the spring-like or clamping action by changing the material of which the pins are made or by enlarging or otherwise altering the contacting portions of the arms. The whole purpose here was to increase the clamping effect of the pin arms, on the assumption that any increased clamping pressure in the arms of straight, or crimped pins, would give desired results.

Following considerable study, applicant has discovered that it is not merely necessary to clamp strands of hair to keep them in place but such strands must be undulated in a direction transversely of their length. Also, that these undulations must be of only slight extent, numerous, and the clamping action of the pin causing such undulations must be sufficient to produce this result but insufficient to so bend or deform the strands that they will break. In this connection, it is pointed out that the hair of one person differs materially from the hair of another person in strand size, stiffness, texture, etc., and that pins placed on the market, to give satisfaction, must be capable of gathering and securing strands of hair in any position without becoming loosened or causing hair breakage.

It is believed the present invention discloses a structure that fully meets the requirements of individual and commercial users in that such structure is well suited to and serves its purpose adequately in the maintaining of coiffures without the need of considering the quality or condition of the hair of the user, and this therefore constitutes an important object of the invention.

2

Another object of the invention lies in the provision of a hairpin that includes multiple cooperative parts by which to engage, bend and hold strands of hair.

5 A further object of the invention lies in the provision of a hairpin having clamping arms that serve to sufficiently undulate strands of hair to secure them in a given position without danger of hair strand breakage, or without possibility of pin loosening.

Other objects and advantages of the invention will be more fully understood from a consideration of the following specification, taken in conjunction with the accompanying drawing; and

15 in which:

Fig. 1 is a side elevational view of a hairpin embodying one form of the invention;

Fig. 2 is a longitudinal sectional view, taken substantially as suggested by the line 2—2 of 20 Fig. 3;

Fig. 3 is a plan view showing the smaller interfitting arm on top;

Fig. 4 is a further plan view showing the receiving arm on top;

25 Fig. 5 is an enlarged fragmentary sectional view of the hairpin arms and shows approximately the undulations of strands of hair as produced by the arm;

Fig. 6 is an enlarged transverse sectional view 30 taken as suggested at 6—6 of Fig. 5;

Figs. 7 and 8 are plan views of modifications of the invention.

Referring more particularly to the drawing, the reference numeral 19 is employed to generally designate a hairpin embodying one form of the invention. The pin comprises a pair of arms 11 and 12 that, at corresponding ends, are integral with a closed or U-shaped end 13. The end 13 serves to normally urge arms 11 and 12 into desired pressure contact. Arm 11 consists of a straight member of usual hairpin length. However, this arm is preferably somewhat wider than the usual hairpin arm and, through a portion of its length, is provided with a series of slots 14. The slots 14 are of elongated nature and, as shown in Figs. 3 and 4, are rectangular. Preferably, these slots are of uniform length and spacing and extend from adjacent the leg end 50 somewhat beyond the longitudinal center of the leg. Beyond the innermost slot 14, there may be provided a further slot 16 which is of somewhat greater length and is for a purpose herein-after set out. At the point of joining of leg 11 with the end 13, said leg is preferably tapered, as suggested at 17, and the loop 18 of the end 13 is of much narrower stock. This lesser width of stock is continued throughout the length of leg 12.

60 Leg 12 is shown to be shorter than leg 11 solely for the purpose of more readily enabling a user of the hairpin to separate the ends when the hairpin is to be engaged with strands of hair. Throughout a considerable portion of the length

of leg 12, it is formed with a series of undulations or rounded bends 19. The free end 21 of this leg is preferably straight, substantially as indicated, and from this end a first bend 22 occurs in a downwardly direction, being so proportioned as to be capable of partially projecting into the endmost slot 14 of leg 11. Continuing from the bend 22 is a reverse or upwardly directed bend 23 which at all times is above and out of contact with the leg 11 and spans the area of the leg 11 between the first and second slot 14. The number of undulations or alternate downwardly and upwardly directed bends depends on the length of the hairpin and, of course, the sharpness of said bends. In the present disclosure four downwardly directed bends 22 are shown and four upwardly directed bends 23. From the last, upper bend 23, the leg 12 curves downwardly and then upwardly to blend with the closed end 13. This last partial bend 24 is accommodated in the slot 16.

Due to the spring action of the closed end 13, the hairpin, when not in use, appears substantially as shown in Figs. 1 and 2 of the drawing. That is, the lowermost bends 22 and 24 project into and partially through the slots 14 and 16. The extent to which the legs interfit is, of course, limited by contact with the ends of the slots 14 and, of course, if a greater or lesser interfitting of the legs is desired, the length of the slots 14 will be correspondingly altered.

Fig. 7, a modification of the structure described, shows a hairpin 26 that includes a leg 27 having slots 28 and 29 that differ from slots 14 and 16 only at their ends. The ends of these slots are rounded, as indicated at 31, it being believed that with certain conditions or qualities of hair the interfitting of bends with this type of slot might be more efficient.

With reference to Fig. 8, it will be noted that a hairpin 32 is shown to have a leg 33 in which slots 34 are generally diamond shaped. Here again, it is believed that this shape slot will also be better suited for use in securing strands of coarse or heavy hair by reason of a less accurate and close interfitting of the bends of the other leg of the hairpin with this shaped slot.

Attention is now directed to Figs. 5 and 6 of the drawing wherein applicant suggests, as nearly as possible, the actual manner in which strands or locks of hair are separated and clamped between the legs of the pin. Of course, the legs of the pin are separated against the spring-like tension of the closed end 13. Following this, the opened end is slipped onto a lock of hair and, upon releasing the legs of the pin, the lower bends 22 crowd hair into the slots 14, forming them into generally U-shaped bends. The hair is not bent to an extent that it is subject to breakage and yet is bent or undulated to an extent that the pin cannot readily slide or slip, or the strands become displaced. Of course, certain strands will be located in the space 36 between the upper bend 23 of leg 12 and the solid area between slots 14. Here strands of hair will be clamped to at least the same extent that strands are now clamped by conventional hairpins and it is believed that with this clamping added to the clamping action effected by bending the hair as suggested in Fig. 6, the pin will firmly hold in place.

Although applicant has shown and described only one form of hairpin in which locks or strands of hair are bent or undulated to provide an improved clamping or securing action and several

forms of slots for the interfitting of the legs of the hairpin, it will be understood that variations of this structure may be made and are contemplated insofar as they are within the spirit and scope of the invention as set out in the annexed claims.

Having thus set forth my invention, what I claim as new and for which I desire protection by Letters Patent is:

- 10 1. A hairpin comprising a pair of legs connected at corresponding ends by a curved resilient part, one of said legs being formed with a series of uniformly spaced elongated slots arranged in the direction of the leg length and extending from adjacent the resilient part to the leg end, a series of undulations extending throughout a considerable portion of the length of the other of said legs and adapted to interfit said slots.
- 15 2. A hairpin comprising a pair of legs, a generally U-shaped end portion integral with corresponding ends of said legs, one of said legs being formed with a series of identically proportioned and spaced slots arranged in the direction of the length of said one leg and extending from adjacent said end portion toward the leg end, uniformly sized and spaced undulations formed in the other of said legs, alternate undulations being adapted to interfit said slots.
- 20 3. A hairpin comprising a pair of substantially coextensive legs, a return bent end portion integral with corresponding ends of said legs, said portion being spring-like and normally causing said legs to have pressure contact throughout their length, one of said legs being formed with a series of elongated slots arranged lengthwise of said one leg and extending from the one leg end to adjacent said end portion, undulations formed in the other of said legs, alternate undulations projecting into said slots under compulsion of said spring-like portion.
- 25 4. A hairpin comprising a pair of substantially coextensive legs, a spring-like portion integral with corresponding ends of said legs, one of said legs being formed with a series of uniformly spaced slots arranged in the direction of the length of the leg, a series of rounded bends extending from that face of the other of said legs adjacent the first mentioned leg, said bends being spaced lengthwise of said other leg to normally project into said slots under compulsion of said spring-like portion.
- 30 5. A hairpin comprising a pair of substantially coextensive legs, a spring-like portion integral with corresponding ends of said legs, one of said legs being formed with a series of uniformly spaced slots arranged in the direction of the length of the leg, undulations formed in the other of said legs, said undulations being so sized and arranged with respect to the first mentioned leg and the slots therein as to be capable of securing alternate strands of hair by deflection and clamping.

ANTHONY V. RICHETTI.
